his ATTORNEYS.

Patented May 20, 1924.

UNITED STATES PATENT OFFICE.

WILLIAM CONAMA, OF ROCHESTER, MINNESOTA; RICHARD MANAHAN ADMINISTRATOR DE BONIS NON OF SAID WILLIAM CONAMA, DECEASED.

BILLIARD TABLE.

Application filed March 22, 1920, Serial No. 367,764. Renewed March 12, 1924.

To all whom it may concern:

Be it known that I, WILLIAM CONAMA, a citizen of the United States, residing at Rochester, in the county of Olmsted and 5 State of Minnesota, have invented certain new and useful Improvements in Billiard Tables, of which the following is a specification.

My invention relates to an improvement 10 in billiard table rails.

The object is to so construct or reconstruct a billiard-table rail that it will have a 15 rack for balls formed in one of the rails, where the balls can be kept until the game is played, making them easily accessible at any time.

In the accompanying drawings:

Fig. 1 is a plan view;

Fig. 2 is a section; and

20 Fig. 3 is a modification.

A, is an ordinary billiard-table, and 1 is a groove cut in one of the rails 2 of 25 a billiard or pocket-billiard table. This is of suitable depth and proportions so that about one-half of the ball extends down into the groove, while the remaining half is above the level of the rail.

In this way, a rack for the balls is right

on the table where the balls can be kept conveniently until the game is played, from 30 which groove they can be easily picked out and placed back on the table.

As a slight modification of this invention, the form shown in Fig. 3 might be adopted, 35 in which a piece of wood 2' is attached to the rail already on the billiard or pocket billiard table in order to widen out the groove 3, thus affording more space for said groove than would be allowed in the original rail itself.

Different devices would have to be used 40 for the reconstruction of different tables, but the fundamental idea of this invention is to construct a rail, or reconstruct one, so that a rack is provided in the rail of the 45 billiard table for the balls.

I claim:

As an article of manufacture, a billiard-table rail made of two longitudinal parts 50 having a rack partly formed in both, so that the two form complements of each other, said rack being of a length adapted to receive a full complement of pocket-billiard balls.

In testimony whereof I affix my signature.

WILLIAM CONAMA.
